[57] CLAIM

The ornamental design for a horseshoe for a front hoof, as shown and described.

DESCRIPTION

FIG. 1 is a front elevational view of a horseshoe for a front hoof showing my new design;

FIG. 2 is a bottom plan view thereof;

FIG. 3 is a fragmentary side elevational view taken along line 3—3 of FIG. 2;

FIG. 4 is a side elevational view of FIG. 1, the opposite side being a mirror image of the side shown;

FIG. 5 is a cross sectional view taken on line 5—5 of FIG. 3;

FIG. 6 is a front elevational view of a second embodiment of the horseshoe for a front hoof shown in FIG. 1;

FIG. 7 is a bottom plan view of FIG. 6;

FIG. 8 is a fragmentary side elevational view taken along line 8—8 of FIG. 7;

FIG. 9 is a side elevational view of FIG. 6, the opposite side being a mirror image of the side shown;

FIG. 10 is a cross sectional view taken on line 10—10 of FIG. 8;

FIG. 11 is a front elevational view of a third embodiment of the front horseshoe shown in FIG. 1;

FIG. 12 is a bottom plan view of FIG. 11;

FIG. 13 is a fragmentary side elevational view taken along line 13—13 of FIG. 12;

FIG. 14 is a side elevational view of FIG. 11, the opposite side being a mirror image of the side shown; and

FIG. 15 is a cross sectional view taken on line 15—15 of FIG. 13.

FIG. 1FIG. 2FIG. 4FIG. 3FIG. 5FIG. 6FIG. 7FIG. 9FIG. 8FIG. 10FIG. 11FIG. 12FIG. 14FIG. 13FIG. 15
